UNITED STATES PATENT OFFICE

2,555,228

BED SIDE GUARD

Alfred T. Evers, Chicago, Ill.

Application February 27, 1948, Serial No. 11,530

2 Claims. (Cl. 5—331)

1

This invention relates to certain new and useful improvements in Bed Side Guard and more particularly to an attachment which, when associated with a bed, will serve to guard against the occupant of the bed rolling or falling off the bed.

An object of the invention is the provision of an attachment of this character which will be simple in construction, inexpensive in manufacture, easy of adjustment with respect to the bed, and which is durable in use.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a conventional bed showing my attachment associated therewith;

Fig. 2 is an elevational view of the side panel of the attachment embodying my invention;

Fig. 3 is a plan view of the bottom panel embodying my invention;

Fig. 4 is an end elevational view; and

Fig. 5 is a fragmentary sectional detail view of a portion of the bottom panel showing a modified form of construction.

My improved bed attachment includes a side panel 10. This side panel 10 comprises a substantially U-shaped frame 11, comprising a top bar 12 from which extend substantially at right angles with respect thereto parallel side bars 13. Within this peripheral frame 11, is a flexible panel 14, preferably formed of suitable cloth fabric. This fabric panel 14 is attached to the peripheral frame 11 by means of suitable clips 15. The side bars 13 extend beyond the bottom edge 16 of the panel 14, and inwardly of their end portions there is provided an enlargement 17. This enlargement 17 may be formed as an integral part of these side bars 13 or by a separate part frictionally fitted thereon.

My attachment further includes a bottom panel 18 comprising a peripheral frame including a crossbar 19 and side bars 20 extending parallel with respect to each other and braced in spaced relation by means of a rod 21.

The ends of the side bars 20 provide socket-bearing members 22 into the sockets 23 of which are adapted to frictionally fit the end portions 24 of the side bars 13 for removably connecting the side panel 10 to, and in a position substantially at right angles with respect to, the bottom panel 20. The enlargements 17 limit the insertion of the end portions 24 into the sockets.

2

The crossbar 19 carries spaced roller elements 25.

In use the bottom panel 18 is disposed between the mattress 26 and the spring 27 of the bed 5. The roller-like elements 25 will contact adjacent coils 29 of the bed spring and serve to retard movement of the panel 18 from beneath the mattress 26. In this position of the attachment, the side panel 10 will extend above the top surface of the mattress 26 and thereby serve to guard against the rolling of a person off the mattress 26.

If desired, there may be two of such attachments employed, one on each side of the bed.

15 When not in use the side panel 10 is removed from the bottom panel 18 and placed upon the bottom panel 18 beneath the mattress 26 for storage purposes. The entire attachment or the side panel 10 alone may be stored in other places, such as a closet or the like, but for convenience the storage may be beneath the mattress 26.

In Fig. 5 the roller element 25 is mounted upon a U-shaped bend 30 formed in the crossbar 19.

25 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

30 1. An attachment for a bed comprising an elongated piece of fabric, a peripheral frame for the cloth fabric including a crossbar and oppositely parallelly extending side bars extending substantially at right angles with respect to the crossbar, a bottom panel adapted to be disposed between the spring and the mattress of a bed, spaced socket-bearing members on said bottom panel, the lower end portions of said side bars 40 removably inserted in the sockets of said members to connect the fabric frame to the bottom panel in a position substantially at right angles with respect thereto, the bottom panel having roller means adapted for engagement with adjacent portions of said spring.

45 2. An attachment for a bed comprising an elongated piece of cloth fabric, a peripheral frame for the fabric including a crossbar and oppositely parallelly extending side bars extending substantially at right angles with respect to the cross-

bar, a bottom panel adapted to be disposed between the spring and the mattress of a bed, spaced socket-bearing members on said bottom panel, the lower end portions of said side bars removably inserted in the sockets of said members to connect the fabric frame to the bottom panel in a position substantially at right angles with respect thereto, and means on said side bars to limit the insertion of the end portions thereof in the sockets of said socket-bearing members. 10

ALFRED T. EVERSON.
